UNITED STATES PATENT OFFICE.

CHARLES A. GARRETT, OF PHILADELPHIA, PENNSYLVANIA.

PRINTING ATTACHMENT FOR CAP-FORMING MACHINES.

Application filed August 23, 1921. Serial No. 494,469.

To all whom it may concern:

Be it known that I, CHARLES A. GARRETT, a citizen of the United States, residing in the city of Philadelphia, county of Philadelphia, and State of Pennsylvania, have invented an Improved Printing Attachment for Cap-Forming Machines, of which the following is a specification.

My invention relates to mechanism for printing successive sections of a strip or sheet of material, generally fibre paper, in synchronism with the operation of means for forming caps or disks suitable for closing bottles and containers, as such material is fed intermittently through the coordinated printing and dieing mechanism.

A primary object of my invention is to provide a relatively simple and efficient printing mechanism that can be attached and used in cooperation with known dieing mechanisms, for the purpose specified.

The characteristic features of my improvements are embodied in the machine set out in the following description and the accompanying drawings in illustration thereof.

In the drawings, Fig. 1 is a front elevation of a known form of apparatus for producing container caps, in combination with the printing attachment of my invention; Fig. 2 is a front elevation on an enlarged scale of the printing attachment illustrated in Fig. 1; Fig. 3 is a broken sectional view taken on the line 3*-3* of Fig. 2; Fig. 4 is a broken sectional view similar to that of Fig. 5 with the parts in a second position; Fig. 5 is a top plan view of a construction of the printing attachment with the head or stationary platen removed; Fig. 6 is a broken sectional view taken on the line 6*-6* of Fig. 5.

The machine illustrated comprises a cap or disk forming mechanism having a frame provided with the bed 1 and the housing 2. The crank shaft 3, journalled in the housing, is driven by the wheel 3' and operates the connecting rods 4 and 5 to reciprocate the male dieing and cutting devices 6 and 7 which cooperate with the female dieing mechanism 8 in forming the caps from a sheet of material A fed thereto intermittently through a guide 9, the sections of the sheet being perforated by the mechanism 10 connected in cooperating relation with the reciprocating dieing mechanism, if this should be desired by reason of the character of the cover to be formed.

The printing attachment illustrated comprises the frame having a bed 1' on which is mounted a slide 2' adjustable on the bed by a screw 1'' journalled therein and engaging the lugs 2'' on the slide or carriage.

A sprocket wheel 11, fixed on and revolved by the shaft 3, drives the sprocket chain 12 which passes over the idler sprockets 13 fixed to the sliding frame 2' and under the sprocket wheel 14 fixed on the shaft 15 which is journalled in that frame. A bevel gear 16, fixed on the shaft 15, drives a bevel gear 17 fixed on a shaft 18 journalled in the frame, the latter shaft having a disk 19 fixed thereto. A crank pin 20, fixed eccentrically in the disk 19, operates a rod 21 connected by a universal joint 22 with a dog 23 having a pivotal connection 24 with a slide 25 adapted to be reciprocated along the ways 26 carried by the frame 2', the slide 25 being provided with the slotted block 25' through which the sheet A is drawn and with the recess 25'' in which the serrated jaw 23' of the dog is movable to engage and disengage the strip with reference to the block and slide; so that in the forward movement of the slide, through the action of the parts 19, 20 and 21 on the dog, the latter will engage the strip to the block and carry said strip forward, while in the rearward movement of the slide, through the action of the said parts thereon, the dog is retracted and the strip disengaged.

A dog 27 is fixed on the shaft 28 journalled in the frame in position to engage the strip A to the stationary bearing 27' over which it is drawn, the dog being held in frictional engagement with the strip by the action on the arm 29 fixed in the shaft 28 of the coiled spring 30 having one end connected to said arm and the other fixed to the frame, the sheet passing between the parts 27 and 27' from the guide roller 31 journalled in the frame.

Parallel webs or tracks 32 are positioned for carrying the strip under the printing head 33, detachably fixed to the frame by the screws 34, said strip being fed forward intermittently to simultaneously position different sections thereof so that during the intervals of rest they will be first printed and the printed sections then formed by the dieing mechanism.

The printing is effected by a printing form 35 carried in a frame or block 36 adapted to be oscillated on the bearings 37,

so that the form can be engaged with the strip A in its periods of rest and press the same against the part 33 to effect the printing operation intermittently, and so that the 5 printing form can be withdrawn from the strip and re-inked during the step by step forward movements on the strip.

The oscillatory printing mechanism is operated through the bearing 38 on the part 10 36 connected by the pin 39 with a link 40 which is connected by a pin 41 with an arm 42 on the ring or band 43 of the eccentric 44, the latter being fixed eccentrically on and revolved by the shaft 15. An arm 45 fixed 15 on the part 36 carries a roller 46 which acts in the curved way 47 of an arm 48, the latter being fixed on a shaft 49 journalled in the frame. Arms 50 fixed to the shaft 49 are connected by pins 51 with links 52 20 engaged by the pins 53 to respective arms 54 adapted to rock on the shaft 15. An ink roller 55 has its end pintles journalled in slide bearings 55' engaged in the bifurcated ends 54' of the arms 54, the rollers 25 being drawn inwardly by coiled springs 56 connected with the arms and slide bearings. The roller runs upon and its movement is controlled by guide bars 47' fixed to the frame, the guide ways being so formed and 30 the mechanism so timed that in the lowered inclined position of the oscillatory part 36 the roller will move over the type or printing form and ink the same, and in the upward movement of the part 36 the roller 35 will be withdrawn therefrom to effect re-inking in engagement with the roller 58.

An ink font 59 supplies ink to the roller 58, the latter being revolved in the ink 40 through the connection of the sprocket wheel 60 thereon by a sprocket chain 61 with a sprocket wheel 62 fixed on the shaft 15.

It will now be understood that the rotation of the shaft is transmitted through the sprocket chain 12 to the shaft 15 and therefore 45 through and through shaft 18, disk 19, and rod 21 to rock the dog 23 and cause it to grip and advance the sheet A under the roller 31, dog 27, between guides 32 and platen 33, through the guide 9 and under the dies 50 6 and 7 which are meanwhile being elevated by the connecting rods 4 and 5. In synchronization with this forward movement of the sheet A, the bed 36 is lowered by the action of the eccentric 44 and through the 55 arm 45 rocks the crank 48, shaft 49, crank 51 and link 52 to oscillate the arms 54 and cause the roller 55 to move over and ink the form 35, the roller having been inked by contact with and revolution by the inking roller 60 58 driven from the shaft 15.

When the slide 25 carrying the dog 23 has reached its forward limit of movement and begins its rearward movement, the pull of the link 21 retracts the toothed part 23 from 65 the sheet A, which is held stationary by the

dog 27. While the sheet is thus held motionless, the bed 46 is elevated thereby moving the roller 55 back to the roller 58 and imprinting the desired impression on the sheet, which is maintained by the guides 32 against 70 the platen 33. The synchronized descent of the dies 6 and 7 cuts from the printed sheet the desired caps or closures. To secure perfect registration of the cutting dies relatively to the impression, the slide 2 is adjusted by means of the screw 1" and lugs 2".

Having described my invention, I claim:

1. A machine for forming and printing closures comprising dieing mechanism, printing mechanism, and feeding mechanism, said feeding mechanism comprising means for advancing a sheet of material to said printing and dieing mechanism in sequence and means for holding said sheet against movement during the operation 85 thereon of said printing and dieing mechanism.

2. In a machine for forming and printing articles, the combination of dieing mechanism, stock feeding mechanism, printing mechanism, means comprising a revoluble shaft for operating said dieing mechanism against one side of a sheet fed through said machine, a revoluble shaft connected with and operated by said shaft first named, 90 means comprising eccentric mechanism operated by said shaft second named for operating said feeding mechanism, and means comprising an eccentric mechanism whereby said shaft second named operates said printing mechanism against the opposite side of a sheet fed through said machine.

3. In a machine for forming and printing articles, the combination with mechanism for printing a surface of a sheet, of a female die engaging such surface, and a male die for engaging the surface of said sheet opposite said printed surface and coacting with said female die to form a cap.

4. In a machine for forming and printing closures, the combination of a slide, dieing mechanism, printing mechanism and feeding mechanism, the printing and feeding mechanisms aforesaid being mounted upon said slide and adjustable by the movement 110 thereof relatively to the dieing mechanism.

5. A machine for forming and printing closures comprising dieing mechanism, printing mechanism and feeding mechanism, said feeding mechanism comprising a slide, a dog pivotally connected with said slide, a crank connected with said dog for rocking it and reciprocating said slide, means comprising a shaft continuously rotatable in the same direction for operating said crank, and means connected with said shaft for operating said printing mechanism.

6. A machine for forming and printing closures comprising dieing mechanism,

printing mechanism and feeding mechanism, said feeding mechanism comprising a slide, means comprising a revolute shaft for reciprocating said slide, and means connected with said shaft for oscillating said printing mechanism about an axis parallel with the direction of movement of said slide.

5 7. A mechanism of the class described comprising feeding mechanism consisting of a slide having means for engaging a strip, an eccentric for reciprocating said slide, a shaft for operating said eccentric, a second shaft having an axis parallel with the di-

rection of movement of said slide for rotating said first named shaft, an eccentric connected with said second named shaft, a ring on said last named eccentric, a platen oscillatable about an axis parallel with said second named shaft, a link connecting said ring and platen, and inking mechanism operable by the oscillation of said platen.

10 Signed at Philadelphia, in the county of Philadelphia and State of Pennsylvania, this 16th day of Aug., 1921.

CHARLES A. GARRETT.
